HEAT EXCHANGER

Ray A. Sandberg, Waukegan, Ill., assignor to
 Houdaille-Hershey Corporation, Detroit, Mich.,
 a corporation of Michigan

Application February 8, 1950, Serial No. 143,010

10 Claims. (Cl. 257—256)

1

The present invention relates to a heat exchanger and to a method of making the same. More particularly, the present invention relates to a heat exchanger of the plate and tube type provided with means for greatly increasing the effective area of the exchanger, and to a method for making such an exchanger.

Tube and plate type exchangers of the prior art typically comprise a heat conductive backing plate on which a continuous length of tubing is secured, as by brazing or welding, to provide a conduit for the flow of heated or refrigerated fluid. In my copending application Serial No. 80,240, filed March 8, 1949, now abandoned, and entitled "Heat Exchanger and Method of Making the Same," I have disclosed the employment of a backing plate which is deformed into tightly gripping effective heat transfer relation with a tube to eliminate the necessity of a separate welding or brazing step. Reference is also made to my copending application Serial No. 206,531, filed January 18, 1951, disclosing common subject matter.

The present invention now provides an improved heat exchanger in which the effective heat exchange area of the unit is greatly increased while at the same time maintaining highly efficient heat transfer contact between the plate surfaces and the exchanger tube.

More particularly, the present invention contemplates the provision of a main backing plate of good heat conductive properties and an auxiliary heat conductive plate having spaced elongated portions secured to the backing plate and intermediate portions spaced from the backing plate to provide an additional heat exchange surface. The heat exchanger tube is secured in the assembly at the area of contact between the two heat conductive surfaces, so that effective heat transfer between the tube and each of the heat conductive members is attained. In addition, these cooperating heat conductive members provide channels or stacks for the flow of a gaseous medium, such as air, into contact therewith to increase the heat transfer efficiency of the unit.

The method of the present invention contemplates the formation of elongated spaced parallel grooves in contacting portions of the main and auxiliary plate members, the positioning of a tube within the grooves, and the deformation of each of the plate members to overlie a median diameter of the tube portions bottomed in the grooves to securely lock both of the heat dissipating members and the tube into a secure, thermally efficient assembly.

2

The advantages of the present invention reside in the increased efficiency of the exchanger due to the effective channeling of the gaseous medium to be heated or cooled and to the effective heat transfer relation between the tube and each of the plate members.

It is, therefore, an important object of the present invention to provide an improved heat exchanger of the plate and tube type having a greatly increased heat exchange area.

Another important object of the present invention is to provide an improved method of making a heat exchanger by the securing of a tube to the exchanger by the deformation of a plurality of plate members into greater than semi-peripheral contact with the tube.

A further important object of the present invention is to provide an improved heat exchange panel including a pair of plate members and a tube secured to the members in effective heat transfer relation, the plate members cooperating to define therebetween gaseous flow passages and a heat transfer surface of increased area.

It is still another important object of the present invention to provide an improved method for making a tube and plate type heat exchanger including the steps of grooving a pair of heat conductive plates, positioning a heat exchange tube in the grooves thus formed, and deforming grooved portions of both of the plates to overlie a median diameter of the tube, thereby interlocking the tube and the plates into a thermally efficient assembly.

Other and further important objects of this invention will be apparent from the disclosures in the specification and the accompanying drawings.

On the drawings:

Figure 1 is a plan view of a heat exchanger of the present invention;

Figure 2 is a fragmentary, enlarged sectional view taken along the plane II—II of Figure 1; and

Figure 3 is a fragmentary, enlarged sectional view, similar to Figure 2, illustrating a step in the method of making the heat exchanger of Figure 1.

As shown on the drawings:

In Figure 1, the reference numeral 10 refers generally to a heat exchanger of the present invention including a sinuous tube 11 having straight parallel portions 12 extending along the length of the exchanger 10 and arcuate portions 13 joining the straight portions 12 and extending beyond the confines of the heat exchanger 10.

In Figure 2, it will be seen that the straight

parallel portions 12 of the tube 11 are secured to a backing plate 14 and a supplementary plate 15. Both plates are formed of thin sheet metal having good thermal conductive properties, such as mild steel. The backing plate 14 is provided with parallel marginal upstanding flanges 16 deformed from the plane of the plate 14. The flanges 16 are apertured as at 17 at spaced points along their length to facilitate assembly of the heat exchanger 10 in a desired position, as on a refrigerator or the like.

The supplementary heat conductive plate 15, which is preferably of lighter gauge than the plate 14, is provided with parallel, longitudinally extending raised portions 18 which extend along the length of the backing plate 14 between the flanges 16 and generally parallel to the flanges 16 and the tube straight portions 12. The raised portions 18 of the member 15 are provided with transversely extending raised reinforcing ribs 19. The height of the raised portions 18 is such that the upper surface of the ribs is displaced from the mean plane of the plate 14 to a distance approximately equal to or slightly less than the height of the end flanges 16.

The auxiliary plate 15 is provided with inclined web portions 20 joining the raised portions 18 to intermediate web portions 21 of the plate 15. The web portions 21 of the auxiliary plate 15 and a corresponding portion of the backing plate 14 are employed to lock the straight tube portions 12 within the assembly as hereinafter described.

The method of assembly (Figure 3) includes, first, the initial deformation of each of the plates 14 and 15 to provide a plurality of parallel, spaced depressions or grooves 22 and 23 in the plates 14 and 15, respectively. The grooves 22 and 23 have arcuate bottoms 22a and 23a, respectively, and upstanding parallel side walls 22b and 23b, respectively. The grooves 22 and 23 may be formed simultaneously following the positioning of the supplementary plates 15 upon the backing plate 14, or the grooves may be separately formed in each of the plates for registry upon initial assembly. In any event, each of the grooves extends uniformly along the length of the respective plates so that upon assembly the coextensive grooves 22 and 23 are nested, as shown in Figure 3.

The straight tube portions 12 are inserted in the grooves 23 which, in turn, are nested in the grooves 22. The radius of curvature of the arcuate bottom 23a of the groove 23 is substantially that of the exterior surface of the tube, while the radius of curvature of the interior surface of the groove 22 is substantially that of the exterior surface of the groove 23 so that smooth mating engagement is attained. It will also be noted that the depth of the groove 23 is substantially greater than the diameter of the tube 11.

It will be seen that only the straight portions 12 of the tube 11 are bottomed within the groove 23. This eliminates the necessity of forming sinuous grooves in the plates 14 and 15, inasmuch as the arcuate joining portions 13 of the tube 11 are allowed to project beyond the side extremities of the plates 14 and 15 of the finished exchanger 10.

The securing of the tube 11 to the plates 14 and 15 within the grooves 22 and 23 may be carried out by means of apparatus such as that illustrated in the above-identified copending application or by other suitable means for swaging or otherwise deforming the upstanding side

walls 22b and 23b of the grooves 22 and 23, respectively, to overlie a median diameter of the straight tube portions 12. This deformation of the grooved side walls may be carried out by either a rolling or a stamping operation. As a result of the deformation of both plates, the mating portions of the plates 14 and 15 are deformed to overlie greater than semi-peripheral portions of the tube 12. The deformation is such that a pair of additional grooves 24 and 25 are formed alongside of and parallel to the main grooves 22 and 23 in the plates 14 and 15, respectively. These additional or supplementary grooves 24 and 25 are contiguous to and coextensive with the lengths of the main grooves 22 and 23, and metal intermediate the supplemental grooves and the main groove of each plate is actually deformed inwardly of the tube to overlie the tube 12, as at 26 and 27.

The area of contact of the plates 14 and 15 is coextensive with the area of the grooves 22 and 24 of the backing plate 14 and the area of the grooves 23 and 25 of the plate 15. The contact area thus includes the metal of the plates 14 and 15 partially surrounding the tube 12 and the immediately contiguous plate areas of the supplemental grooves formed on interlocking the plates and the grooves.

There is no actual surface contact between the backing plate 14 and the tube portion 12. However, the backing plate portions 26 are deformed so as to overlie a median diameter of the tube, thereby locking the plate through the tube in a firm interlocking engagement. These same interlocking portions 26 of the plate 14 in combination with the tube portions 12 secure the auxiliary plate 15 to the plate 14.

Upon the assembly of the heat exchanger 10 in operative position, as, for instance, supported upon the back surface of a refrigerator or the like, with the parallel lengths of tubing extending vertically, the supporting surface cooperates with the ribs 19 formed on the raised auxiliary plate portions 18 to define therewith a plurality of channels with the tube portions 12 in one of the channel walls. Also, the raised portions 18 and the backing plate 14 cooperate to define additional channels therebetween. The raised ribs 19 not only serve to reinforce the raised portions 18 of the plate 14, but these ribs serve to space the raised portions 18 from a supporting surface so that minimum interference with heat transfer from the portion 19 is offered. It will be seen that the auxiliary heat exchanger plate 15 serves to divide air flow between the flanges 16 into a plurality of different columns or stacks. Thus, each side of the surfaces 18 and 20, and those surfaces of the auxiliary plate overlying the backing plate, may effectively serve as heat dissipation surfaces. In addition, those surfaces of the backing plate 14 underlying the raised portions 18 of the plate 15 also serve as heat dissipating surfaces. The auxiliary plate thus more than doubles the effective heat dissipating surface of the heat exchanger. The channeled separation of air or other gaseous coolant also increases air circulation and turbulence, so that all of the coolant medium is effectively employed.

It will be understood that modifications and variations may be effected without departing from the scope of the novel concepts of the present invention.

I claim as my invention:

1. The method of making a heat exchanger which comprises forming a pair of parallel

grooves in a first metal plate spaced a preselected extent of the first plate apart, forming a pair of parallel grooves in a second metal plate spaced a preselected extent of said second plate apart, said last mentioned extent being greater than said first mentioned extent and with respective grooves of said first and second plates nesting one within the other, bottoming a tube in the inner of said nesting grooves, and deforming the side walls of each of said grooves and intermediate contiguous portions of each of said plates radially inward of the tube to overlie a median diameter of said tube, thereby securely locking the tube in said grooves and said plates to one another in efficient heat transfer relation.

2. A heat exchanger comprising a backing plate, an auxiliary plate having spaced portions contacting said backing plate and intermediate offset portions forming a coolant flow channel therebetween, and a sinuous tube for confining a flowing heat exchange fluid having portions secured within coextensive nesting grooves formed in contacting portions of said auxiliary plate and said backing plate, said tube being in greater than semi-peripheral surface contact with said auxiliary plate and in efficient heat transfer relation with both said auxiliary plate and said backing plate.

3. A heat exchanger comprising a backing plate having a plurality of elongated parallel grooves extending thereacross, an auxiliary plate also having a plurality of grooves extending thereacross and nested within the grooves of said backing plate in surface contact therewith, said auxiliary plate having portions intermediate the grooves therein spaced from corresponding portions of said backing plate and a sinuous tube seated in said nesting grooves and secured therein by being in greater than semi-peripheral surface contact with the grooves of said plates.

4. A heat exchanger comprising a sinuous tube having straight parallel portions joined by arcuate intermediate portions, a first heat conducting plate having spaced grooves receiving the straight parallel tube portions with said arcuate intermediate portions of the tube extending beyond said first plate, said grooves being in greater than semi-peripheral surface contact with said tube to secure the same thereto, and a heat conductive backing plate having parallel spaced grooves extending thereacross receiving the grooved portions of said first plate coextensive and interlocked therewith to secure said backing plate to said first plate, said plates having other portions spaced apart to define coolant flow passages therebetween intermediate the straight portions of said tube.

5. In a heat exchanger including a backing plate having parallel spaced grooves, a sinuous tube having parallel portions secured within said grooves, an auxiliary heat dissipating plate comprising spaced parallel groove portions nesting with the grooves of said backing plate and interposed between said backing plate and said tube, said grooved portions being interlocked with said backing plate in effective heat transfer relationship therewith and in extended surface contact with said tube, and said auxiliary plate having additional portions intermediate said grooved portions offset from the plane of said backing plate and cooperating therewith to define a gas flow passage.

6. A heat exchanger comprising a backing plate, an auxiliary plate having spaced portions contacting portions of said backing plate and an

intermediate offset portion forming with said backing plate a coolant flow channel, said backing plate and said auxiliary plate having elongated nesting grooves in the contacting portions of said auxiliary plate and said backing plate, and a tube for confining a flowing heat exchanger fluid, said tube having portions secured within said elongated nesting grooves in efficient heat transfer relation with both said auxiliary plate and said backing plate.

7. A heat exchanger for attachment to a substantially plane supporting surface, comprising a thermally conductive metal backing plate having end flanges for contacting said supporting surface, said flanges and said backing plate cooperating with said surfaces to define a primary coolant flow channel, an auxiliary plate having spaced portions contacting portions of said backing plate and intermediate offset portions forming with said backing plate a secondary coolant flow channel, said backing plate and said auxiliary plate having elongated nesting grooves formed in the contacting portions of said auxiliary plate and said backing plate, and a tube for confining a flowing heat exchanger fluid, said tube having portions secured within said coextensive nesting grooves in efficient heat transfer relationship with both said auxiliary plate and said backing plate.

8. A heat exchanger for attachment to a substantially plane supporting surface, comprising a thermally conductive metal backing plate having end flanges for contacting said supporting surface, said flanges and said backing plate cooperating with said surface to define a first coolant channel, an auxiliary plate having spaced portions contacting portions of said backing plate and intermediate offset portions forming with said backing plate a second coolant flow channel, said contacting portions of said auxiliary plate and said tube backing plate having elongated nesting grooves therein, and a tube for confining a flowing heat exchange fluid, said tube having portions secured within said elongated nesting grooves in efficient heat transfer relation with both said auxiliary plate and said backing plate.

9. A heat exchanger for attachment to a substantially plane supporting surface, comprising a thermally conductive metal backing plate having end flanges for contacting said supporting surface, said flanges and said backing plate cooperating with said surface to define a primary coolant flow channel, an auxiliary plate having spaced portions contacting portions of said backing plate and intermediate offset portions forming with said backing plate a secondary coolant flow channel, said backing plate and said auxiliary plate having elongated nesting grooves formed in the contacting portions of said auxiliary plate and said backing plate, and a tube for confining a flowing heat exchange fluid, said tube having portions secured within said elongated nesting grooves and in efficient heat transfer relationship with both said auxiliary plate and said backing plate.

10. In a heat exchanger including a backing plate having parallel spaced grooves, a sinuous tube having parallel portions secured within said grooves, an auxiliary heat dissipating plate having a grooved portion nesting with one of said grooves of said backing plate and interposed between said backing plate and said tube, said grooved portions being interlocked with each other and with said tube portion secured therein and in effective heat transfer relationship there-

with and said auxiliary plate having projections extending from the plane of said backing plate and at a substantial angle thereto between adjacent grooves and cooperating with said backing plate to increase the heat exchange efficiency of 5 the heat exchanger.
